U.S. Cl. D9—83

FIG. 4

FIG. 5

FIG. 6

FIGURE 1 is a front elevational view of a combined decanter and closure therefor embodying my new design; FIGURE 2 is an exploded rear elevational;

FIGURE 3 is a top plan view with the closure mounted on the decanter;

FIGURE 4 is a top plan view of the decanter with the closure removed;

FIGURE 5 is a bottom plan view; and

FIGURE 6 is a sectional view thereof taken along the line 6-6 of FIG. 1.

The dominant features of my design reside in the portions shown in full lines.

I claim:

The ornamental design for a combined decanter and closure therefor, as shown and described.
